[57] CLAIM

The ornamental design for a combination cordless handset telephone and base therefor, as shown and described.

DESCRIPTION

FIG. 1 is a front perspective view of a combination cordless handset telephone and base therefor showing my new design;

FIG. 2 is a front elevational view of the base on an enlarged scale, the hand set being omitted for convenience of illustration;

FIG. 3 is a right side elevational view thereof;

FIG. 4 is a left side elevational view thereof;

FIG. 5 is a rear elevational view thereof;

FIG. 6 is a top plan view thereof;

FIG. 7 is a top plan view of the handset on an enlarged scale, the base being omitted for purposes of disclosure;

FIG. 8 is a right side elevational view thereof;

FIG. 9 is a left side elevational view thereof;

FIG. 10 is a rear elevational view thereof;

FIG. 11 is a top plan view thereof; and,

FIG. 12 is a bottom plan view thereof.

The bottom surface of the base is flat and unornamented except for the four feet. The keys in broken lines on the handset and base are shown for illustrative purposes only and form no part of the claimed design.
